UNITED STATES PATENT OFFICE

113,733

DESIGN FOR A TABLE COOKER

Simon W. Farber, Brooklyn, N. Y.

Application January 21, 1939, Serial No. 82,508

Term of patent 14 years

To whom it may concern:

Be it known that I, Simon W. Farber, a citizen of the United States, residing at Brooklyn, county of Kings, and State of New York, have invented a new, original, and ornamental Design for a Table Cooker, of which the following is a specification, reference being had to the accompanying drawing, forming part thereof, wherein:

Fig. 1 is a perspective view, and

Fig. 2 is a top plan view, of a table cooker showing my new design.

I claim:

The ornamental design for a table cooker, substantially as shown.

SIMON W. FARBER.
